Patented Feb. 17, 1920.

Inventor:

John F. Reilly,
by his attorney,
Charles N. Gooding.

UNITED STATES PATENT OFFICE.

JOHN F. REILLY, OF SOMERVILLE, MASSACHUSETTS.

TOOL FOR SEVERING METAL BARS.

1,331,212.

Specification of Letters Patent. Patented Feb. 17, 1920.

Application filed November 16, 1918. Serial No. 262,865.

To all whom it may concern:

Be it known that I, JOHN F. REILLY, a citizen of the United States, residing at Somerville, in the county of Middlesex and 5 State of Massachusetts, have invented new and useful Improvements in Tools for Severing Metal Bars, of which the following is a specification.

This invention relates to tools for severing metal bars and is especially adapted to severing bars of hard brittle metal such for example as bars of unannealed tool steel. These bars are very difficult to sever by cutting and when so severed it is customary to 10 grind a groove around the bar at the point where it is desired to sever it by means of an emery wheel, and to then break the bar at the grooved portion thereof, or said bars may be cut by heating the same and cutting 15 them while hot. These different processes are slow and expensive.

It is the object of this invention to provide a convenient tool for use in shops which is adapted to hold the metal bar firmly in position, and then by manually operating a bender, to crack the bar at the point where it is held by the tool and thus sever a portion thereof from the bar.

The invention resides in the means by 30 which the bar is held and in the means for bending the bar while so held.

The invention further consists in the combination and arrangement of parts set forth in the following specification and particularly pointed out in the claims.

Referring to the drawings, Figure 1 is a plan view of my improved tool for severing metal bars.

Fig. 2 is a sectional elevation taken on line 2—2, Fig. 1.

Fig. 3 is a sectional elevation taken on line 3—3, Fig. 1.

Fig. 4 is a detail section taken on the line 4—4 of Fig. 1.

Like numerals refer to like parts throughout the several views of the drawings.

In the drawings, 5 is a holder, having a flange 6 thereon. A gripper 7 is slidably mounted on the holder 5 and has a bearing 50 edge 8 adapted to bear against one side of a metal bar 9, the opposite side of said bar resting against the straight edge 10 of the flange 6, said bar also resting against the face 11 of the holder 5. The gripper 7 is 55 slidably mounted on the holder 5 and is provided with a screw threaded shank 12,

which extends through a hole 13 in the holder 5, and which is adjusted to move the bearing edge 8 toward or away from the straight edge 10 of the flange 6 by an adjusting nut 14. The gripper 7 and the flange portion 6 of the holder 5 form together a clamp for rigidly holding the bar which is to be severed in position during the severing operation. 65

A bender 15 is slidably mounted in ways 16 provided in the holder 5, and is held in position in said ways by a cap plate 17. The bender 15 is moved away from the bar 9 by a spring 18, which is connected at one end 70 thereof to a screw 19, which is fastened to the bender 15, and at the opposite end said spring is attached to a plate 20, which is attached at its lower end by a screw 21 to the holder 5. The bender 15 is moved toward 75 the bar 9 to bend the same and cause it to be severed by two pairs of toggle links 22, 23 and 24, 25. These toggle links are mounted on the holder 5 between a pair of levers 26 and 27, which are pivoted at 28 and 29 80 respectively to the holder 5. The upper ends of the links 22 and 24 are rounded off and enter corresponding recesses provided in the lower end of the bender 15. The lower ends of the links 22 and 24 are piv- 85 otally connected to the upper ends of the links 23 and 25, said links 22 and 24 being forked at 22' and 24' whereby they may receive tongues 23' and 25' respectively formed upon the links 23 and 25. These adjacent 90 ends of the said links are also rounded to fit each other and although not pinned together they cannot become separated when the tool is assembled. The lower ends of the links 23 and 25 are rounded off and enter 95 correspondingly shaped recesses provided in the holder 5. The inner faces of the levers 26 and 27 are provided with U-shaped ears 30 and 31 respectively, which bear against the links 22 and 24. The upper end 100 of the bender 15 is rounded at 32 where it bears against the edge of the bar 9.

The general operation of the device hereinbefore specifically described is as follows: The bar 9 is placed upon the face 11 of 105 the holder 5, with its lower edge bearing against the straight edge 10 of the flange 6 on said holder. The gripper 7 is then operated by means of the nut 14 to move the bearing edge 8 of said gripper against one edge 110 of the bar 9.

It will be noted that the median longi-

tudinal line of the shank 12 of the gripper converges toward the median longitudinal line of the bender 15, and that said lines converge toward a point located at the same 5 side of the bar 9 as that upon which the gripper is located, and on the opposite side of said bar from that upon which said bender is located.

The arrangement of the converging me- 10 dian lines of the tool is for the following purpose: viz, that when the bar 9 has been bent by the bender 15 to such an extent that it is ready to break or crack off, the portion so bent will then be substantially at right 15 angles to the median line of the bender 15.

The bar having thus been firmly clamped in position, the operator moves the handles 26 and 27 toward each other, thus moving the oppositely disposed pairs of links toward 20 each other, and causing the bender slide 15 to move forwardly as toward the bar 9. A continuation of this movement will cause the bar to be bent very slightly upward, and being held firmly by the bearing edge 8 of 25 the gripper 7, said bar will be cracked off transversely thereof, and in alinement with the bearing edge 8, as at the dotted line A, Fig. 1.

The handles are now moved apart and the 30 spring 18 operates to cause the bender 15 to move rearwardly. The tool is now in readiness to be used for another severing operation.

I claim:

35 1. A tool for severing metal bars, having in combination, a clamp adapted to hold a metal bar, a bender adapted to engage said bar at one side of said clamp, and a pair of levers adapted to move said bender trans- 40 versely of said bar, whereby said tool may be manually operated.

2. A tool for severing metal bars, having in combination, a clamp comprising a holder and a gripper adapted to press said bar 45 against said holder, a bender adapted to engage said bar at one side of said gripper, and a pair of levers adapted to move said bender transversely of said bar, whereby said tool may be manually operated.

50 3. A tool for severing metal bars, having in combination, a clamp comprising a holder and a gripper with a bearing edge adapted to contact with said bar transversely thereof and press it against said holder, a bender 55 adapted to engage said bar at one side of said gripper, and a pair of levers adapted to move said bender transversely of said bar, whereby said tool may be manually operated.

4. A tool for severing metal bars, having 60 in combination, a clamp comprising a holder and a gripper with a bearing edge adapted to contact with said bar transversely thereof and press it against said holder, a bender having a rounded end adapted to engage 65 said bar at one side of said gripper, and a

pair of levers adapted to move said bender transversely of said bar, whereby said tool may be manually operated.

5. A tool for severing metal bars, having in combination, a clamp adapted to hold a metal bar, a bender adapted to engage said bar at one side of said clamp, and means to move said bender transversely of said bar, the median longitudinal lines of said gripper and bender converging toward a point lo- 70 cated on the same side of said bar as said gripper and on the opposite side of said bar from said bender. 75

6. A tool for severing metal bars, having in combination, a holder, a flange on said holder, a gripper slidable on said holder toward and away from said flange, means to move said gripper toward said flange, whereby a bar may be clamped between said gripper and flange, a bender slidably mounted on said holder at one side of said gripper and adapted to engage said bar, and a pair of levers adapted to move said bender trans- 80 versely of said bar, whereby said tool may be manually operated. 85

7. A tool for severing metal bars, having in combination, a holder, a flange on said holder, a gripper slidable on said holder toward and away from said flange, means to move said gripper toward said flange, whereby a bar may be clamped between said gripper and flange, a bender slidably mounted on said holder at one side of said gripper and adapted to engage said bar, toggle links mounted on said holder and engaging said bender, and levers adapted to engage said links, whereby said bender may be manually moved transversely of said bar. 90

8. A tool for severing metal bars, having in combination, a holder, a flange on said holder, a gripper slidable on said holder toward and away from said flange, means to move said gripper toward said flange, whereby a bar may be clamped between said gripper and flange, a bender slidably mounted on said holder at one side of said gripper and adapted to engage said bar, a pair of levers pivoted to said holder, two pairs of oppositely disposed toggle links mounted on said holder between said levers, each of said 100 pairs of links being pivotally connected together, the end of one link of each of said pairs of links being arranged to bear against said bender, and one end of each of the other links of said pairs of links bearing against 105 said holder, whereby said bender may be moved transversely of said bar. 110

9. A tool for severing metal bars, having in combination, a holder, a flange on said holder, a gripper slidable on said holder toward and away from said flange, means to move said gripper toward said flange, whereby a bar may be clamped between said gripper and flange, a bender slidably mounted on said holder at one side of said gripper 115

120

125

130

and adapted to engage said bar, a pair of levers pivoted to said holder, two pairs of oppositely disposed toggle links mounted on said holder between said levers, each of said 5 pairs of links being pivotally connected together, the end of one link of each of said pairs of links being arranged to bear against said bender, and one end of each of the other links of said pairs of links bearing against 10 said holder, whereby said bender may be moved toward and transversely of said bar,

and a spring connected to said bender and to said holder, whereby said bender may be moved away from said bar.

In testimony whereof I have hereunto set 15 my hand in presence of two subscribing witnesses.

JOHN F. REILLY.
